AUTOMATIC FABRIC PICKER-OFF AND FEEDING MACHINE

Ricardo M. Smith and John G. Gogal, Passaic,
N. J.

Application February 16, 1937, Serial No. 125,994

3 Claims. (Cl. 271—34)

This invention relates to a machine for the purpose of picking off individual pieces from a pile or stack of cut or torn fabric material.

The commercial operation of this machine is for the purpose of picking off individual pieces of fabric material from a pile or stack lying at an angle to the machine and feeding the individual pieces to another point of process or manufacture. This machine will apply to all types of woven fabric.

The invention also consists of various details of constructions that are more fully set forth hereinafter and finally embodied in the claims.

The invention is illustrated in the accompanying drawings in which

Figure 1 is a side view of our machine.

Figure 2 is a detail of our coated belt.

Figure 2a is an end view of Figure 2.

Figure 2b is a cross section of the belt.

Figure 3 is a plan view of a machine embodying our invention.

In Figures 4 and 5 is a detail of our cam and lever connections.

In Figure 3 is shown a conveyor consisting of a series of belts, 1, whose outside surface has been specially treated, with emery, for the purpose of picking a fabric piece from the pile in the special container which is directly underneath and to the rear of the belts. The fabric pieces picked off of the pile designated by 2, cling to the series of belts 1 and are conveyed to the roller belts designated by 3, where it is, in turn, conveyed to the presser roller 4.

The forward and backward movement of the container, designated by 5, is caused by the operation of levers designated by 6 and 7. The levers are pinned to a rod designated by 8 and are controlled from the arm, designated by 9 which is pinned to the rod 8.

Figures 4 and 5 are a portion of the side of our machine containing the operation of our side arm lever, designated by 10. Connected to the same rod as lever 10 is the arm designated by 11, which is the connection between the rod and the box cam 12. The function of the lever is performed by moving back, causing the spring end, designated by 13, to release itself from the teeth on the container rack, designated by 14, through pressure against the block designated by 15. A short rise in the box cam 12 causes the levers to release the container allowing it to come forward so the fabric pieces in said container press against the picker-off belts and when the roller passes the rise, the levers force the container back in order to give the piece of fabric, just

picked up, clearance from the rest of the fabric pieces in the stack pile. When the rise of the cam has passed, the lever returns to its original position and the container, designated by 16, is forced back in order to give the fabric piece, which has just been picked up, freedom to move through freely. After the clearance of the piece of fabric, the operation is repeated until the supply in the container has been exhausted. The container, 16, operates on a set of tracks, one side of which is shown designated by 17. These tracks are grooved so that the wheels of the container may set firmly. These tracks are also adjustable for the greater or lesser degree of gravity feed for the container. The tracks are attached to the frame at the points designated by 18 and 19. The track at point 18 is pinned, but at point 19 the joint may be loosened so that the track may be raised or lowered in the slotted portion of the frame designated by 20. The tracks are made adjustable due to the varying weights of the different types of fabrics. A stack of heavy fabric pieces would require less pitch than a stack of light fabric pieces.

Figure 1 is a side view of our machine attached to a standard ironer. The stacked fabric pieces, designated by 21, are placed in the container designated by 22. The upper portion of the fabric pieces rests against the back rest, designated by 23, and the tops of these pieces are in the direct alignment with the picker-off roller and belts designated by 24. In the forward movement of the container, the stack of fabric pieces presses against the picker-off belts and is conveyed to its destination. The upper edge of the fabric piece cannot fall back when being carried around the roller as it has been picked up at a point which is approximately the extreme upper edge of the fabric. We have placed a metal plate under the conveyor belts designated by 25, for the purpose of eliminating the falling of the edges of the fabric piece.

The end of this plate, as is shown in Figure 3, has fingers, designated by 26, projecting between the carrier belts. The fingers guide the piece of fabric material to the drum of the ironer.

Figure 2, reference character 1, is a detail of our coated belt. The V belt has been specially coated with emery. This emery may be attached to the belt by glue, shellac, blastings, etc. 27 designates the coating on the outside face of the belt.

What we claim is:

1. An automatic fabric piece separator, comprising a set of adjustable inclined tracks, a con-

5 tainer for work pieces, rearwardly inclined, standing on edge, supported for intermittent gravity movement on said tracks to present the front piece of the pack with different pressures to a friction separator.

5 2. In the device of claim 1, levers for releasing the container allowing it to move the work pieces toward the friction separator and then force the container back after an individual piece has made contact with the friction separator.

10 3. In the device of claim 1, levers for releasing the container allowing it to move the work pieces

toward the friction separator and then force the container back after an individual piece has made contact with the friction separator, ratchets carried at the sides of the container, pawls on the levers for engaging the ratchets, blocks for releasing the pawls from the racks near the limit of the levers' forward movement and cams for operating said levers in timed relation with the separator. 5

RICARDO M. SMITH.
